WILLIAM A. GOODHER, OF BURLINGTON, NEW JERSEY.

Letters Patent No. 60,877, dated January 1, 1867.

COOKING RANGE.

The Schedule referred to in these Letters Patent and making part of the same.

TO ALL WHOM IT MAY CONCERN:

Be it known that I, WILLIAM A. GOODHER, of Burlington, New Jersey, have invented an improved Portable Range; and I do hereby declare the following to be a full, clear, and exact description of reference being had to the accompanying drawing, and to the letters of reference marked thereon.

My invention consists of the combination with the fire-place and ovens of a cooking range of certain pipes, the whole being constructed and arranged as fully described hereinafter, so that the undue heat of the outer casing is prevented, while a continuous supply of heated air may be either thrown out into or directed to the chimney; the range being thus available for either winter or summer use.

In order to enable others skilled in the art to make and use my invention, I will now proceed to describe the manner of carrying the same into effect.

On reference to the accompanying drawing, which forms a part of this specification—

Figure 1 is a sectional elevation of my improved cooking range.

Figure 2, a section on the line 1 2, fig. 1; and

Figure 3, a plan view of the range with the top plate removed.

A is the outer casing of the range, within which is a smaller casing, B, and within the latter are the ovens C C', and a fire-place, D, in which is the usual grate. To the front end of the outer casing are hung the doors a, of the two ovens, and the door b of the ash-pit. The sides and ends of the ash-pit and fire-place are made with slabs, c c' d d', of fire brick, and at the back of the fire-place, above the slab d', is the usual water tank. Both the casings, A, B, are covered by the top plate, F, in which are the usual openings, e e. Between the ovens C C' and the casing B, is a space or flue, f, which communicates through an opening, g, with an upright pipe, G, and each of these pipes communicates at its upper end with a horizontal drum, H, which is secured to the outer casing, I, attached to the top plate F. To the drum, H, are connected two vertical pipes, J, former extending through the top of the drum to the chimney, and the latter communicating through the opening, i, with the ash-pit; and in each pipe, G G J', is a valve, j, the stem of which projects through the top of the casing I. A short pipe, k, extends from the drum H through the front of the casing I, and is closed at its outer end with a cap. At the back of the casing, A, is a sliding door, l, and in the front of the same, near the lower edge of the same, are openings, x x. In the top and back of the casing I, are openings of suitable form, and in the pipe J is an opening, q, to which is fitted a slide, s, for a purpose described. When a fire is kindled in the fire-place D, the products of combustion will pass over the tops of the ovens through the flues f, through the openings g, pipes G G, drum H, and pipe J, to the chimney. When the fire is raked the valve in the pipe J' is turned so as to allow the dust to pass from the ash-pit through the opening i to the pipe J' and to the drum H, in which it accumulates, and from which it is removed through the pipe k. The ordinary ranges are so constructed that the heat is either always thrown out into the air, or is wasted by being absorbed by the surrounding brick-work, the range in either case being available during part of the year only; those ranges which throw out the heat being serviceable only in winter, those in which the heat is absorbed by the brick-work can be used only in summer. For this reason houses are provided with both winter and summer ranges. In the improved range above described the heat given off from the inner casing and passes through the opening g to the chimney, so that during the winter the outer casing is prevented from being heated to an objectionable extent. During the winter, however, the slide s is lowered so as to close the opening g, when the heated air within the casings will be discharged through the openings in the top and back of the casing I into the room. Should the quantity of heated air supplied be more than sufficient to warm the room in which the range is placed, a portion may be conducted to other rooms through suitable pipes.

It will be seen that by the use of a range of this description the necessity of employing two ranges for different seasons of the year is avoided. It will also be seen that a range of this character is simple in construction, may be made at a slight expense, and may be readily moved from place to place.

I claim as my invention, and desire to secure by Letters Patent—

The ovens C C', and fire-place D, in combination with the casings A and B, and pipes G G, and equivalents, the whole being constructed and arranged substantially as and for the purpose described.

In testimony whereof I have signed my name to this specification in the presence of two subscribing
